COMBINED GOLF COURSE TEE-OFF MARKER AND CIGARETTE HOLDER

Mark E. Buffamoyer, Rte. 2, Lebanon, Pa.

Filed July 18, 1961, Ser. No. 65,962

Term of patent 14 years

(Cl. D34—5)

The essential features of my design reside in the portions shown in full lines.

I claim:

The ornamental design for a combined golf course

tee-off marker and cigarette holder, as shown and described.
